RELAY

Application filed July 13, 1927, Serial No. 205,307, and in Germany June 24, 1926.

Our invention refers to relays, and more especially to protective relays serving for automatically disconnecting defective parts of a line system.

5 Hitherto the several parts of an electric line system have been supervised by relays whose time interval for the release grows with growing voltage and diminishes with increasing current. For instance, if the time 55
10 interval for the release is proportional to the quotient of voltage and current, in other words to the resistance of the faulty circuit, the time interval of release is in the well defined linear relation to the distance from the 60
15 faulty point.

In the drawings affixed to this specification and forming part thereof, Figs. 1 and 2 illustrate the characteristics of the systems hitherto used; Fig. 3 illustrates those of the new 20 system according to this invention; and Figs. 4 and 5 show diagrammatically by way of example two forms of a relay embodying our invention.

In Fig. 1 of the drawings, the mode of 25 operation of a line protection as hitherto employed is shown in a graphical manner. On the abscissa axis are plotted the distances between the supervisory stations B, C, D, E, G, from the central station A, the several parts 30 of the line system being thus shown in the correct proportion as to length. On the ordinate axis is plotted in seconds the time after which clear-out relays will be actuated whenever a defect occurs at any point of the line 35 A—G. The relays may be designed, for instance, in such manner and may be connected to current transformers having such transformation ratio that their time interval of release is one second, if the defect occurs within a distance of 10 kilometers and that the interval 40 will be increased a further second for each further 10 kilometers distance. For instance, the time interval of release of the relay stationed at A will thus be found on a straight 45 line intersecting point A, and the same applies also to the time interval of the other relays. In order to provide for the circumstance that the time intervals will never be equal to zero, those parts of the straight lines which adjoin 50 the abscissa axis are drawn in dashes. With

the aid of Fig. 1 the idea underlying the present invention will now be explained.

For instance, if a short circuit F occurs at a distance of 70 kilometers from the central station A, relay D will cut out after the lapse 55
5 of one second. In case that the relay or the switch controlled by it should fail, then, after two seconds the relay at the adjoining station C would effect the disconnection. If this relay also should fail for some reason, or if the switch appertaining to it should fail to disconnect the line, the relay disposed at B would operate after five seconds, or the relay at A after seven seconds. A drawback 60
65 connected with this arrangement lies in the fact that a defect which occurs near the end of a long line system can be provided for only after a comparatively long interval of time. Thus, for instance, a defect occurring at a distance of 48 kilometers from the starting point A would be cut out by the relay arranged at B only after about three seconds. At very great distances of the substations 70
75 from one another these retardations can assume very undesirable values and it has therefore been suggested to adjust the relays either by varying the numbers of windings of the current transformer or by means of regulating resistances in such manner that they 80
85 will disconnect the part of the line system appertaining to them within a sufficiently small time interval predetermined for the system as a whole, even if the defect should occur at the extreme end of the respective 90
95 part of the system.

The time intervals of release in accordance with a system such as just referred to are shown in Fig. 2, where the straight lines representing the time intervals take such a course that at the end of each line section the time interval is equal to one second. As shown in Fig. 2, all straight lines are thus imparted a different inclination. Such an arrangement can, however, give rise to faulty connections. For instance if a defect occurs at F, the relay mounted at D would effect a correct disconnection. However, if this relay should fail disconnection would not be effected by the adjoining relay ar- 100

ranged at C, but by the relay disposed at B, for the straight lines which represent the time intervals of release of these two relays intersect before the faulty point. If the 5 proportionality of the time intervals is provided for only in an approximate manner or, as is frequently the case, if greater deviations from the linear proportion occur, still greater drawbacks will ensue.

10 These drawbacks are obviated according to this invention by causing the rate at which the time interval of release grows with the increase of the quotient of voltage and current to remain constant, no matter how that 15 limit of this quotient is adjusted at which the time interval of release has the desired low value, or, in other words, even in the case where all the relays are adjusted in such manner that they will disconnect a defect 20 near the end of the respective part of the line system after the lapse of one second, the lines which represent their time intervals for operation when the defect occurs beyond the section of the line apportioned to them 25 will nevertheless remain parallel, as is shown in Fig. 3. It is immaterial what the time interval will be if the defect occurs within the part of the line system apportioned to the relay. It is sufficient if the time 30 interval, for instance up to about one half second diminishes still further, in order that in the case of defects occurring a short distance behind one of the relays this relay will be sure to disconnect sooner than the 35 relay apportioned to the preceding part of the system, the time interval of which would amount in this case only to a little more than one second.

According to the present invention, therefore, 40 a maximum time interval for release, say one second may be prescribed for all the sections of the line no matter how long the sections may be or to what extent they may differ in length among themselves, but 45 the time intervals for operating the circuit breakers associated with the relays for defects or short-circuits occurring beyond their respective sections, will be represented by parallel lines, as shown in Fig. 3. In this 50 manner, the disadvantage incident to the operation of known relays according to Fig. 1, wherein the time interval for release may reach undesirable high values, is overcome; and likewise the disadvantage of relays operating according to Fig. 2, namely, the danger of faulty disconnections, is obviated.

The adjustability of the relays can further be provided for, according to this invention, in such manner that the influence of voltage which tends to increase the time interval, is diminished by an adjustable reaction which grows with increasing current. This dependency can better be explained 65 with the aid of some equations. The time

interval T of a relay operating according to Fig. 1 corresponds to the equation

$$T = C \cdot \frac{e}{i},$$

70 where C is a constant value, e the voltage, and i the current of the faulty circuit. Thus means are provided in the quotient relay which increase the time interval with growing voltage, and further means which diminish the interval with growing current. According to this invention, the action of the means influenced by the voltage is opposed by the current, the effect of such current being in direct ratio to its strength, and being adjustable. This adjustable opposing action of the current i will therefore shorten the lag or retardation (time interval) in the 75 release of the relay. In consequence thereof, if a leak or defect should develop exteriorly of the line section apportioned to a particular relay, the new time interval of 80 release of said relay will be.

$$T_1 = C \frac{e - ci}{i} = C \left(\frac{e}{i} - c \right).$$

90 The opposing action of the current is adjusted in accordance with the length of the line section to be protected by the relay. This adjustment has no effect whatever on 95 that increase in the time interval of release of the relay which occurs when a leak or defect occurs in the line at a distance greater than the protective range of the relay. If 100 relays constructed and arranged in accordance with the present invention are located at the same points or intervals as those indicated at A, B, C, D, and E in Fig. 1, and if such new relays are adjusted in such a 105 manner that each relay will, in the event of a short-circuit in the line section apportioned to such relay, respond or become effective within the same length of time, for instance, one second, the characteristic lines 110 representing the action of the several relays, will be parallel in those portions which correspond to line sections lying outside of the individual line sections apportioned to the 115 respective relays. This novel result is shown clearly in Fig. 3.

120 It will be understood that the time intervals for release of a given relay for defects occurring within the section of the line apportioned to said relay need not increase according to any definite mathematical relation and may or may not have a constant rate of increase depending upon the distance of the defect from the relay, provided only that the maximum interval is that predetermined for the section, as, one second. In fact the inertia of the parts, both electrical and mechanical, will complicate the curve 125 representing the intra-sectional intervals of release.

Fig. 4 illustrates in a diagrammatic manner and by way of example a relay embodying this invention.

1 is the line system to be protected, 2 is a Ferrari's disc, and 3 is a slide. The disc 2 is acted upon by a driving magnet 4 which is traversed by the current from a current transformer 5 and tends to turn the Ferrari's disc in the direction of the arrow. A constant magnet 6 is provided for braking the disc. The saturation of the magnet iron 4 and the braking force are balanced in such manner that the velocity of rotation of the Ferrari's disc 2 increases in a linear manner 10 in proportion to the current in the line system 1. The disc 2 is provided with a pair of contacts 7 serving for closing the release circuit, as soon as it is carried by the disc 2 into contact with the slide 3. The slide is 15 acted upon by the magnet core 9 against the action of a spring 8. The magnet core 9 is movable within a voltage coil 10, which is supplied with current from the voltage transformer 11. The curve of contact of 20 slide 3 is so shaped that the distance to be travelled by the pair of contacts 7 is proportional to the voltage. Now the voltage coil 10 is further provided with a current winding 12 which is connected in parallel with 25 the adjustable resistances 13, both being inserted in the circuit of the current transformer 5. As long as the line system is free from defects the Ferrari's disc 2 is prevented from rotating by its nose 14 abutting against 30 an iron core 15 mounted at one end of a double armed lever 16, the other arm of which carries a magnet core 17. The core 15 is controlled by a coil traversed by current from the current transformer 5, the coil 35 of the magnet core 17 is connected to the voltage transformer 11. The current tends to pull the magnet core 15 out of the way of the nose 14, but is counteracted by the magnet core 17. However, if a short circuit occurs 40 the voltage is diminished and the current increases, and in consequence thereof the current will dominate at the lever 16 and will pull the magnet core 15 out of the way of nose 14, thus allowing the disc to rotate 45 with a velocity which is approximately proportional to the short-circuit current. The voltage coil 10 now allows the spring 8 to act on the slide 3, the more so the more the voltage has dropped and therefore the distance 50 to be travelled by the pair of contacts 7 is diminished in proportion, until the contacts meet the curved portion of the slide 3 and thereby close the releasing circuit. However, the voltage coil 10 is counteracted 55 by the current coil 12, so that the slide 3 is displaced still further under the influence of spring 8 and the distance to be travelled by the contacts 7 is diminished still further, the more so the greater the short circuit current. The rate of this diminution can be ad- 60

justed by means of the regulating resistance 13. If this resistance is cut out altogether, the coil 12 is short-circuited and the counteraction against the tendency of the voltage to increase the time interval of release becomes equal to zero. The higher the resistance in the regulating resistance 13 connected in parallel to it, the greater will be the effect of this current coil and the more the time interval of release will be diminished. The current traversing the driving magnet 4 will not be influenced materially by the variation of the regulating resistance 13. 70

The effect of the short circuit current tending to diminish the time interval of release can also be obtained by mechanical means, as shown for example in Fig. 5. Here the short-circuit current of the line system 21 acts by means of the current transformer 22 and connecting wires 23 and 24 on a bimetal rod 25. Under the influence of the heat generated by the current this rod will bend and in doing so will come in contact with the slide 26, as shown in dash lines. This contact will cause a release circuit (not shown) to be 80 closed, which causes the switches to be opened. In the circuit of the bimetal rod is inserted a choking coil 27, the saturation of which is such that the rate of travel of contact 28 is approximately proportional to the current. 85 The position of slide 26 is dependent upon the voltage magnet 29 which is excited by the voltage transformer 30. As long as the current in the line system 21 does not exceed the normal value, the circuit of the bimetal rod 25 is bridged by the connections 31 and contact 32. As soon, however, as the current increases, the current magnet 37 will move a lever 33 counter to the action of spring 34 and the nose 35 will then abut against the 90 contact piece 32 and will remove the short circuit. The bimetal rod is now supplied with current and will travel the distance adjusted by the voltage at the rate dependent upon the current. However, this distance is 100 further dependent upon the position of lever 33 upon which rod 25 is mounted. The fulcrum of this lever can be varied by inserting a bolt in any one of a plurality of holes 36 provided for this purpose. The greater the 105 distance between the fulcrum and the bimetal rod 25, the greater the variation of the position of this rod for a predetermined adjustment of the other arm of the lever, and this adjustment is again the greater, the greater 110 the short circuit current, and the more the contact will travel towards the curve 26, and the smaller will be the distance to be travelled until contact is made. 115

This invention can also be applied without 120 any difficulties to such relays, in which the distance to be travelled by the contact is invariable, while the rate of travelling is directly proportional to the current and inversely proportional to the voltage. Thus 125 130

the voltage here brakes the movement, for instance by developing a counter torque or by braking action. In order to carry the invention into effect the countertorque or the braking action are also made dependent upon the current, and this in such manner that the increasing current causes them to be decreased.

Various changes may be made in the details 10 disclosed in the foregoing specification without departing from the invention or sacrificing the advantages thereof.

We claim:—

1. A protective relay comprising means for 15 automatically cutting out part of a line system after a predetermined time interval, which interval increases in proportion to an increase of voltage and decreases in proportion to an increase in current, and means for 20 setting said relay to operate after a predetermined time interval, with a predetermined value of the quotient of voltage and current, without affecting the increase of the time interval for the operation of the relay in the 25 event the predetermined value of said quotient should be exceeded.

2. A protective relay comprising means for 30 automatically cutting out part of a line system after a predetermined time interval, which interval increases in proportion to an increase of voltage and decreases in proportion to an increase in current, and adjustable means, controlled by the current, for diminishing the influence of the voltage and for 35 setting said relay to operate after a predetermined time interval, with a predetermined value of the quotient of voltage and current, without affecting the increase of the time interval for the operation of the relay in the 40 event the predetermined value of said quotient should be exceeded.

3. A protective relay comprising a movable member for automatically cutting out 45 part of a line system after a predetermined time interval, which interval increases in proportion to an increase of voltage and decreases in proportion to an increase in current, means for moving said movable member at a rate which grows with the current, 50 voltage-controlled means for limiting the distance traversed by said member, and adjustable additional current-controlled means for making said distance dependent upon the current and for setting said relay to operate after a predetermined time interval, with a predetermined value of the quotient of voltage and current, without affecting the increase of the time interval for the operation of the relay in the event the predetermined value of said quotient should be exceeded.

4. A protective relay comprising a movable member for automatically cutting out 60 part of a line system after a predetermined time interval, which interval increases in proportion to an increase of voltage and

decreases in proportion to an increase in current, current-controlled means for moving said movable member, means influenced by the voltage for limiting the distance traversed by said member, and adjustable current-controlled means for opposing the influence of the voltage on said last mentioned means, and for setting said relay to operate after a predetermined time interval, with a predetermined value of the quotient of voltage and current, without affecting the increase of the time interval for the operation of the relay in the event the predetermined value of said quotient should be exceeded.

5. A protective relay comprising means for automatically cutting out part of a line system after a predetermined time interval, which interval increases in proportion to an increase of voltage and decreases in proportion to an increase in current, timing mechanism, a voltage coil associated with said timing mechanism and operative to increase said time interval, a second, oppositely directed winding associated with said coil and traversed by a regulatable current corresponding to the current in the faulty circuit, and means for adjusting said current for setting said relay to operate after a predetermined time interval, with a predetermined value of the quotient of voltage and current, without affecting the increase of the time interval for the operation of the relay in the event the predetermined value of said quotient should be exceeded.

6. A protective relay comprising a movable member for automatically cutting out part of a line system after a predetermined time interval, which interval increases in proportion to an increase of voltage and decreases in proportion to an increase in current, current-controlled means for moving said movable member at a rate which grows with the current, voltage-controlled means for limiting the distance traversed by said member, adjustable additional current-controlled means for making said distance dependent upon the current and for setting said relay to operate after a predetermined time interval, with a predetermined value of the quotient of voltage and current, without affecting the increase of the time interval for the operation of the relay in the event the predetermined value of said quotient should be exceeded, and current-controlled mechanism for maintaining said movable member in initial position.

7. A protective relay comprising a movable member for automatically cutting out part of a line system after a predetermined time interval, which interval increases in proportion to an increase of voltage and decreases in proportion to an increase in current, current-controlled means for moving said movable member at a rate which grows

with the current, voltage-controlled means for limiting the distance traversed by said member, and adjustable additional current-controlled means for making said distance dependent upon the current, including a double-armed lever, one arm of which determines the initial position of said movable member, a current-controlled magnet adapted to influence the other arm of said lever to move the same, and means for varying the fulcrum of said lever, whereby said relay is set to operate after a predetermined time interval, with a predetermined value of the quotient of voltage and current, without affecting the increase of the time interval for the operation of the relay in the event the predetermined value of said quotient should be exceeded.

8. A protective relay for automatically cutting out a defective part of a line system after a predetermined time interval, and apportioned to a definite section of said line system, including a pair of contact members, and adjustable mechanism controlled by the line current and voltage and adapted to be set to close said contacts within a predetermined time interval when the quotient of voltage and current has attained a predetermined value corresponding to the length of said apportioned section of the line, said mechanism including voltage-controlled means operative to maintain the rate of increase of said time interval constant when said predetermined value of the quotient of voltage and current is exceeded, whereby the rate of increase of said time interval for defects occurring beyond said section is independent of the length of said section.

In testimony whereof we affix our signatures.

MANFRED SCHLEICHER.
